(57) **CLAIM**

The ornamental design for a glove, as shown and described.

DESCRIPTION

FIG. 1 is a top perspective view of a glove;
FIG. 2 is a bottom perspective view of the glove;
FIG. 3 is a top view of the glove;
FIG. 4 is bottom view of the glove;
FIG. 5 is a side view of the glove;
FIG. 6 is another side view of the glove;
FIG. 7 is an end view of the glove; and,
FIG. 8 is another end view of the glove.

The broken lines shown in the figures represent portions of the glove and form part of the claimed design. Portions of the glove that are not shown form no part of the claimed design. The stippling in the figures represents a contrast in appearance and does not depict any particular color or texture. A right-hand glove is depicted in the Figures, it being understood that a left-hand version of the glove would be of mirror image appearance.
